APPARATUS FOR HOMOGENEOUS
SPRAYING FILM

Charles N. Edwards, Prince Georges County, Md.

Application September 18, 1950, Serial No. 185,489

5 Claims. (Cl. 95—94)

(Granted under Title 35, U. S. Code (1952),
sec. 266)

1

This invention relates to a cyclo-sprayer for applying liquids, solutions, or powders to a surface or a support.

More particularly the invention is directed to a cyclo-sprayer which will evenly spray and homogeneously apply liquids, solutions or powders as a single or multiple coating to flexible or non-flexible permeable or non-permeable surfaces or supports which may be stationary or in motion. The size of the device may be very small in comparison to the surface treated. It does not clog, wear or leak in any normal usage, does not require excessive precision manufacture and is easily assembled and disassembled. Additionally its operation is not dependent on the use of supplementary pressure or pumps and hence it need not be subject to the difficulties resulting from pressure variations frequently occurring in this type equipment. It may however be advantageously used in pressure systems.

Prior methods of applying coatings or solutions to a surface are many and varied but all appear to be of limited application or inherently unsuited for the primary purposes of the present improvements. Dipping a surface or support usually involves difficulty in controlling the quantity of liquid adhering to the support or surface notwithstanding the use of such expedients as varying the texture of the surface or the viscosity of the solution. Brushes, squeegees or rollers frequently produce streaks or leave foreign bodies on the surface and do not provide the constant flow required for some installations.

Prior pressure sprays or jets place severe limitations on the system in which they are used. The pressure must be constantly uniform to achieve uniform and homogeneous application, and all parts are under pressures which subject the auxiliary equipment to potential leakage or eruption. These prior pressure spray techniques fail to evenly and homogeneously apply solutions to large areas unless the spray nozzle is excessively distant from the support or surface being sprayed. Small orifices such as are used in forming jets are easily clogged and rendered useless by the presence of foreign bodies or solid particles in the system.

Other difficulties arising from the use of common forms of jets include that of properly spacing the orifices for different film speeds and the difficulty of obtaining even development of the film. For example, the use of non-intersecting jets may result in too rapid oxidation during the period moving film is not being subjected to the spray, while intersecting jets may create whirl-

2

pool currents on the treated material so as to cause uneven development. The use of pneumatic atomizers to provide a spray or mist is virtually prohibitive when active reducing agents are present in the solution or liquid, because they are oxidized before they can be supplied to the surface to be treated.

The present improvements are particularly suited for and will be described in connection with a rapid photographic film processing device, in which is provided a supply of treating liquid connected to the central portion of a slotted receptacle. The receptacle may be cylindrical and a slit or slits may be transversely disposed in its outer wall. It has been found that a single slit is sufficient for satisfactory operation with developing and fixing liquids. When a plurality of slits is used they should be shaped and/or arranged so that liquid dispensed through different openings will not intersect before being imposed on the surface to be treated so as to result in deleterious uneven application similar to that resulting from intersection of liquids moving in cone like configurations from spaced pressure jets.

The inner surface of the slotted wall may be quite smooth and not interrupted by projecting elements such as vanes. A somewhat rough surface is not objectionable, but it is preferred that any projections or fins which are used be very short so as to avoid excessive movement about the inner wall. It will be seen that both the illustrated embodiments provide for the even flow of liquid.

The developing, fixing, or rinse liquid is preferably introduced centrally of the drum or cylinder as through a hollow entrance tube or bearing. After the liquid enters the chamber it falls by gravitational force toward the bottom and contacts the inner peripheral wall or previously introduced liquid either of which it is believed, rapidly imparts a high velocity to the incoming liquid. The linear velocity attained by the liquid prior to leaving the cylinder approximates that of the wall. The rapidly moving liquid is forced through the slit, which forms a restricted passage for dispensing the liquid, by centrifugal force.

The treating liquid has a ribbon like form on leaving the slit. The speed of rotation of the drum or dispenser is such that liquid is simultaneously being directed outwardly from the opening toward the treated surface over the 360° of rotation. For example, the speed of rotation may approximate 5000 revolutions per minute. The result is that material moving through a loop

or partial loop configuration may be treated by a uniform and adequate amount of liquid during its entire passage through the configuration.

Another advantage is that where a substantially complete loop is made or where the projected liquid strikes the top of the housing, the projected liquid will prevent movement of previously upwardly dispensed liquid from falling on the lower portion of material being treated. Instead, it will be driven to the side and run down 10 the side of the housing to the drain.

The use of vanes within the cylinder is optional rather than essential. When used they may be radially disposed for a portion of the distance between the center of the cylinder and the inner periphery of the cylinder so as to provide both for ready entrance of the material to be dispensed and for its movement along the inner periphery of the cylinder as mentioned above.

An object of invention is to provide an improved device for uniformly applying liquids or powders to a surface to be treated.

Another object is to provide a cyclo-sprayer rotatably mounted and having an opening in its peripheral wall which uniformly dispenses 25 material during rotation of the cyclo-sprayer.

Another object is to provide a rotatably mounted dispensing device which is connected to a source of rotary power and to a supply of treating material which is so constructed that the 30 incoming material may move to the inner wall of the dispensing device and attain a substantial velocity before being ejected from the dispensing device by centrifugal force.

Another object is to provide a method of simultaneously and uniformly treating a length of material.

Another object is to provide a method of continuously processing exposed motion picture film by forming it into a loop or partial loop configuration and approximately simultaneously applying a treating liquid by projecting it on the entire inside surface of the loop.

Another object is to provide a cyclo-spray device which is uniformly effective over the width of the material to be treated and for 360° and which operates with sufficient force and speed to prevent liquid applied to a surface above the cyclo-spray from falling on material positioned below it.

Another object is to provide a cyclo-spray device particularly well suited for dispensing the fluids used in developing photographic film.

Another object is to provide a light weight means for rapidly processing photographic film. These and other objects will be manifest from a consideration of the following description, claims and drawing in which:

Fig. 1 is a diagrammatic partly broken away view of a single unit of the cyclo-spray device showing the driving motor and gravity type liquid feed, together with a bottom supply tank which may be used.

Fig. 2 is an exploded view showing the manner of mounting the spray unit on the driving motor, the inner construction of one side of a spray drum modified by having radially disposed vanes secured to it and how the spray unit may be assembled.

Referring to the drawings, Fig. 1 depicts a hollow cylinder or receptacle 10, i. e. without radially disposed vanes, which is slit as at 12 and supported for rapid rotation by electric or other motor 14. During operation the member 16 (Fig. 2) is fixed to projection 18 of the cyclo-

4
spray drum side 20 in a manner so that rotation of the motor will cause rotation of the drum. An entrance bearing 22 for developing liquid, hypo or other liquid is centrally positioned on the opposite side 23 of the cylinder 10. The cylinder rotates relatively to the bearing 22 which has a fitting extension for connection to flexible or other tube 24 through which liquid may be fed by gravity or other pressure from supply tank 25 or sucked through from tank 26. The tank 26 may function as a drainage tank in a circulating system (not shown), as a supply tank, or as both a supply and drainage tank depending on particular desires or requirements. It may be vented as at 28.

As will be understood the tube 24 may be connected to liquid supply tank 25 for gravity or other pressure feed or may be inserted in vented tank 26 as at 30.

A housing 32 integral with tank 26 and perpendicularly disposed thereto has ingress passage 34 and an egress slit 36 leading to another chamber (not shown) for the entering moving picture film in other material 35, a plurality of roller guides such as 37, 38, 39, 40, and 41 form the film into a loop partially or nearly completely round the centrally disposed cyclo-spray unit as desired or required for the continuous processing being carried out.

The guides may be spool shaped to avoid damaging contact with the film. The dispensed liquid may drain into tank 26 through the drain shown at 42.

The slit at 12 is preferably as long or slightly longer than the width of the material to be treated so that the substantially 360° spray dispensed during operation will prevent liquid applied to the top reach on portion of material in the housing from falling on the lower portion. Drum 42 is provided to remove the spent or otherwise excess liquid. The housing has a door portion 44 which forms a side of the housing and which can be latched in any convenient manner. The hose 24 passes through the opening 46 of the door to a selected supply tank.

Referring specifically to Fig. 2, in which like parts in Fig. 1 have been given like numerals, the side 20 has secured thereto radially disposed vanes. These vanes permit ready entrance of the centrally introduced treating liquid and extend to a distance short of the inner periphery of the slotted portion. The vanes may accordingly function during operation to force the treating liquid to the inner periphery and yet do not interfere with its subsequent movement for dispensing as above described.

The film 35 is suitably driven or drawn through the housing 32 by means (not shown) at a predetermined and uniform rate. While only a single unit is shown it will be understood that a plurality of such units may be used in the continuous development of motion picture film or other material which may be receiving a number of treatments or coatings.

Assuming the illustrated unit to be used for projecting high speed developing liquid of a type known per se, the incoming material moves through the housing or chamber 32 as previously described. After leaving through opening 36 it may again be looped or festooned as desired for a rinse followed by a hypo application and final rinses. As before stated the rinse liquid and/or hypo may individually be applied by a similar cyclo-spray unit as shown.

The application of a ribbonlike stream of

liquid as above described in the continuous development of film is believed to constitute a new method which avoids the disadvantages of known methods. It is contemplated that structural changes from the structures specifically shown may sometimes be resorted to in the formation of the ribbon form and the practice of the method.

The application of the developing and hypo-liquid by the cyclo-spray is particularly advantageous. While rinses may be preformed satisfactorily by single or multiple immersions in continuous processing, use of the cyclo-spray for these operations permits a substantial saving in weight which is important as the present invention contemplates a portable unit.

The drawings have been made somewhat diagrammatic to better show the relationship of parts. It is to be understood that selection of materials such as would exclude light from undeveloped film in its movement from its source through passage 34 and the treating chamber of chambers is within the scope of the present invention.

The slit at 12 has been described as transversely of the drum unit. It may however somewhat be angularly disposed on the face of the drum. Excessive angularity will render priming of the unit more awkward because of escape of the liquid. Priming may sometimes be necessary particularly where a suction type feed is used.

The width of the slit may vary within reasonable limits and in accordance with the particular treatment. A width of .013 inches is illustrative of that satisfactorily used in applying liquids in rapid film developing processing in a chamber such as 32 having about four feet of film in the formed loop. A film speed of approximately 60 feet per minute is illustrative rather and limitative of processing rates successfully used. The diameter of the cyclo-spray unit of such a unit may approximate three inches, and its speed of rotation may approximate 5000 revolutions per minute.

It is not desired to be limited to the illustrated and described embodiments but rather by the scope of the appended claims.

The invention described herein may be manufactured and used by or for the Government of the United States of America for governmental purposes without the payment of any royalties thereon or therefor.

I claim:

1. A device for applying treating fluid to continuous surfaces of a strip material, said device including a housing and having a work chamber and having an ingress and egress opening through which material to be treated may continuously move, support means for said strip material mounted in said chamber and arranged so that

a substantially looplike configuration may be formed by said material moving around said support means and through the housing, a rotatable spray unit mounted in said chamber centrally of said loop forming supports, said chamber being completely open between said supports and said spray unit to thereby provide unobstructing passage-ways from the spray unit to the material, and means for rotating said spray unit to dispense treating fluid and direct it through said passage-ways in direct impingement against the entire inside surface of strip material.

2. The combination of claim 1 further defined in that said spray unit is a receptacle with an outer wall having a narrow longitudinal slit extending across said wall through which slit the treating fluid is projected in a fine spray during each complete revolution of the receptacle.

3. A device for homogeneously spraying a liquid on a substantially closed loop of strip material, comprising a housing for said loop of strip material, guide means for said loop mounted in said housing, a hollow cylindrical receptacle mounted for rotation in said housing within said loop, a narrow longitudinal opening in said receptacle, means for admitting said liquid into said receptacle, and means for rotating said receptacle.

4. A device for applying a homogeneous spray to a strip, comprising a hollow housing forming a chamber for said strip, means for movably mounting said strip within said chamber in a substantially closed loop, a rotatable spray device comprising a hollow cylindrical receptacle having an outer wall with a spray opening therein, means for admitting liquid into said receptacle, and means mounting said spray device for rotation in said housing within the loop of said strip.

5. The invention as defined in claim 4 wherein said spray opening is a longitudinal slot in said outer wall.
